UNITED STATES PATENT OFFICE.

JOHN W. B. FARIS, OF SKIPMORE, TEXAS.

HAIR-CUT REGISTER.

No. 873,998.

Specification of Letters Patent.

Patented Dec. 17, 1907.

Application filed February 18, 1907. Serial No. 357,995.

To all whom it may concern:

Be it known that I, JOHN W. B. FARIS, a citizen of the United States, residing at Skidmore, in the county of Bee and State of Texas, have invented a new and useful Hair-Cut Register, of which the following is a specification.

This invention has reference to improvements in registering devices for hair-cuts for the use of barbers, and its object is to provide a means whereby the usual manipulation of the barber's chair in preparing the same for the reception of a customer desiring to have his hair cut and the restoration 10 of the chair to the condition that normally prevails will operate a register or signal or both to make a registration or to give notice that the barber's chair has been so used.

It is customary in preparing a barber's 20 chair for the use of a customer desiring to have his hair cut, for the barber to remove the head-rest, and as the barber usually has a number of customers desiring to be shaved to each customer desiring to have his hair 25 cut it is the custom to replace the head-rest immediately after a customer has had his hair cut.

This invention comprises a means whereby the replacing of the head-rest into the chair 30 will cause the momentary closure of an electric circuit including an electrically operated registering device or a signal or both.

The invention comprises a sliding member 35 movable into the path of the head-rest shank by means of a suitable spring, and this member carries an electric circuit terminal arranged to wipe across a stationary circuit terminal and close the circuit when the head-rest is introduced into the chair, and thereby 40 moves the sliding member against the action of the spring. When the head-rest is removed from the chair the arrangement is such that the sliding member is projected by the spring into the channel provided for the 45 shank of the head-rest, but this is done without closing the electric circuit.

The invention will be fully understood from the following detailed description taken in connection with the accompanying drawings forming part of this specification, in which,—

Figure 1 is a section, with parts in elevation, through a portion of the back of a barber's chair provided with the improved reg-

ister-operating device; and Fig. 2 is a similar 55 section showing a different phase of the operation of the device.

Referring to the drawings, there is shown a portion 1 of the back of a barber's chair in which is arranged a channel 2 for the reception 60 of the shank 3 of an ordinary head-rest.

Adjacent to the channel 2 there is seated in the back 1 of the chair a rectangular casing 4 having one side 5 coincident with one wall of the channel 2, and this side 5 may, if 65 desired, be removable from the other part of the casing for permitting access to the interior thereof.

About midway of the height of this side 5 there is formed through it an opening or 70 channel 6 for the passage of the beveled end 7 of a bar 8. Adjacent to the beveled end 7 the bar 8 has a lug 9 formed thereon acting as a stop for the bar to prevent the beveled end 7 from projecting through the slot 6 75 more than a limited distance into the channel 2. The other end of the bar 8 is carried by an elastic hanger 10 fast at its upper end on a bracket 11 secured to the casing 4, and between the inner end of the bar 8 and the 80 rear wall of the casing is a buffer spring 12. Fast to a block 13 on the inner wall of the side 5 of the casing there is a bracket 14 carrying on its upper end a roller 15 upon which the bar 8 rides and by which it is held out of 85 contact with the lower wall of the slot or passage 6.

Fast on the under face of the bar 8 is a V-shaped bracket, one leg 16 of which is of metal, say, copper or brass, and the other 90 leg 17 of which is of insulating material such as hard rubber or vulcanized fiber. In operative relation to this bracket there is a metallic brush 18 fast on but insulated from a standard 19 rising from the bottom of the 95 casing 4.

Electric conductors 20 lead from the metallic leg 16 and brush 18 respectively to a suitable electric registering device or signal or both. Neither the registering device nor 100 the signal are shown since any approved form of register or signal may be used and such register or signal in itself forms no part of the present invention.

Let it be supposed that the parts are in 105 the position shown in Fig. 1, with the head-rest in place. Under these conditions the block 8 will be pushed by the head-rest into

the casing 4 and the buffer spring 12 will be compressed as shown in Fig. 1. The contact leg 16 will have the relative position to the brush 18 shown in Fig. 1, that is, the insulating portion 17 will be between the brush 18 and the contact leg 16.

When a customer desires to have his hair cut the barber removes the head-rest and then under the action of the spring 12 the block 8 will be moved to the right as viewed in the figures until the end 7 has been projected into the channel 2 and the stop 9 has engaged with the inside wall of the side 5 of the casing. During this motion of the block 8 the insulating portion 17 has wiped past the brush 18, which is made of elastic metal so as to yield for this purpose, but during this movement it will be understood that the circuit to the register or signal has not been closed.

Having completed the hair-cut the barber returns the chair to its normal condition by inserting the head-rest. The lower end of the shank 3 of the head-rest now engages the projecting beveled end 7 of the bar 8 and coacting therewith forces the bar inward against the action of the spring 12 to the position shown in Fig. 1. During this inward movement of the bar 8 the conducting leg 16 has been brought into contact with the brush 18 and has wiped across it. This causes the momentary closure of the electric circuit including the register or signal or both, and the register or signal is operated thereby, but the circuit is again broken before the bar 8 finally comes to rest in the position shown in Fig. 1.

It will thus be seen that every time the barber's chair is returned to the normal condition after a customer has had a hair-cut notice of this has either been recorded on the register or has been audibly given to some authorized person.

The relation of the parts 16 and 17 may, of course, be reversed so that the register or signal will be operated by the removal of the head-rest and not upon its reinsertion.

I claim:—

1. In a barber's chair, a means for registering hair-cuts comprising a removable head-rest a fixed electric terminal, a movable electric terminal, a sliding block carrying the movable terminal and having one end beveled, and a spring tending to move the beveled end of the block into the path of the head-rest of the chair.

2. In a barber's chair, a means for registering hair-cuts comprising a removable head-rest a fixed electric terminal, a movable electric terminal, a sliding block carrying the movable terminal and having one end beveled, an elastic carrier for said block, and a spring tending to move the beveled end of the block into the path of the head-rest of the chair.

3. In a barber's chair, a means for registering hair-cuts comprising a removable head-rest a fixed electric terminal, a sliding block having one end beveled, a spring tending to move the beveled end of the block into the path of the head-rest of the chair, a movable electric terminal carried by the block and arranged in the path of the fixed terminal, and an insulating member also in the path of the fixed terminal and carried by the block and arranged to prevent the closure of the circuit at the electric terminals when the block is moved in one direction.

4. In a barber's chair, a means for registering hair-cuts comprising a removable head-rest a fixed electric terminal, a movable electric terminal, a sliding block carrying the movable terminal and arranged in the path of the head-rest of the chair, and a roller support for that portion of the sliding block adjacent to said head-rest.

In testimony that I claim the foregoing as my own, I have hereto affixed my signature in the presence of two witnesses.

JOHN W. B. FARIS.
